UNITED STATES PATENT OFFICE

MATTHEW J. KEEVERS, OF NORTHAMPTON, MASSACHUSETTS

BUCKLE SUPPORT

Application filed May 9, 1928. Serial No. 276,256.

This invention relates to supports for attaching and holding buckles and similar ornaments upon shoes, slippers, pumps, and other types of footwear, and in the nature of an improvement upon the supports shown in the patent to Fleming No. 1,326,153, dated December 23, 1919, and in my earlier Patent No. 1,377,253, dated May 10, 1921. In these earlier patents a buckle support is shown having two spaced and connected members or jaws between which the vamp of a slipper may be received to detachably connect the support thereto. In these earlier patented structures the gripping surfaces of the jaws or space connected members which engage the vamps are smooth so that the support is held by the inherent spring or resiliency of the jaws. While such a construction has proved to be eminently satisfactory, as evidenced by the extensive use into which these earlier buckle supports have gone, I have found that under some conditions it is desirable to provide the clamping jaws of the support with means which will insure a substantially permanent connection between the holder and the vamp of the shoe or slipper, and thus to obviate entirely the possibility of accidental detachment or displacement of the support and consequently the buckle carried thereby. For instance, while the frictional engaging clamping jaws such as are illustrated in the patents aforesaid, are satisfactory, particularly when used to attach the buckle to the vamp of walking shoes, slippers or pumps wherein the leather is relatively thick or heavy, and in connection with which supports comparatively cheap buckles of cut steel, rhinestone or the like are used for everyday wear, it is desirable, particularly with expensive precious metal or jeweled buckles, used for instance, on evening or dress slippers made of relatively thin material, such as satin, brocade or the like, to positively insure that such expensive buckle shall not be come detached from the slipper and lost, which might possibly occur with the frictional gripping arrangement, especially under the stress and strain of dancing.

Therefore the present improvement is directed to equipping the vamp engaging or

clamping members or jaws of the buckle holder with means for making a substantially permanent connection between the holder or support and the vamp, the construction and arrangement being such that the greater the strain or pull on the holder outward or away from the top of the vamp, the tighter the clamping jaws will grip the material—in other words, the more the tendency of the buckle is to work off from the vamp, the more positive will be the gripping action of the jaws on the vamp.

With the above recited objects and others of a similar nature in view my invention consists in the construction, combination and arrangement of parts set forth and falling within the scope of the appended claim.

In the preferred embodiment of the invention shown in the accompanying drawings

Fig. 1 is a perspective view of a pump provided with a buckle supported in accordance with my invention;

Fig. 2 is a perspective and substantially front view showing the application of the ornament support to a pump;

Fig. 3 is a side elevation of the support shown in Fig. 2;

Fig. 4 is a rear elevation;

Fig. 5 is a sectional view showing the holder engaged in a fragment of a vamp;

Fig. 6 is a plan view of the blank from which the support is made.

The buckle support or holder of the present invention is formed from an integral blank A stamped or cut from a sheet of thin metal into substantially the shape shown in Fig. 6. It will be noted that this blank comprises a base portion 1, having parallel slits 2 to form the shank 3, which connects the base portion with the upper or buckle supporting section 4, the latter being slotted to form the oppositely disposed buckle engaging tongues 5. The base portion 1 of the blank is cut to provide a pair of spaced prongs 6, which are inclined or project upward and inward. Likewise, this base portion of the blank is indented or stamped to form small rounded nibs 7. In forming the blank into the buckle holder or support the base portion is bent or folded transversely along a line adjacent to the in-

ner ends of the slits 2, thus forming a vamp engaging clip or clamp which is substantially U-shaped in cross section, and which clamp is provided with inwardly projecting rounded nibs and upwardly and inwardly extending prongs, which latter are in line with the nibs, but located a little forward or offset to such nibs. The shank 3 between the slits 2 is also bent upwardly and backwardly so that the buckle supporting member or section 4 of the holder is inclined upwardly and rearwardly relative to the clip or clamp and consequently relative to the vamp of the shoe when the holder is attached, as will be shown by reference to Fig. 5. The back or rear edge 8 of the clip section of the holder is concaved to conform to the curved free edge of the vamp, while the jaws or members forming the clip or clamp are curved transversely to conform to the curvature of the instep when the holder is in use, as will be seen by reference to Fig. 5.

In the formation of the holder from the blank the oppositely extending spring tongues 5 are slightly upstruck from the surface of the section 4 and the free ends of the portions of the tongues are sloped in order to permit the ready insertion of the opposite end portions of the ordinary buckle bar 9, as indicated in the dotted lines in Fig. 1.

It will thus be noted that the buckle holder in the present instance comprises as an integral structure, a vamp-clamping member U-shaped in cross section and curved to conform to the curvature of the edge of the vamp and also to the curve of the instep, and that one section of such clamp, in the present instance, the lower section, which fits against the inner side of the vamp, is formed with upwardly and inwardly inclined prongs, which will engage with the material of the slipper or pump at the inner side of the vamp, while the upper section of the clamp has the inwardly extending nibs which will press against the material of the slipper or pump at the outer face of the vamp, and that the prongs, although in line with the nibs, are oppositely disposed relative to the latter and are located forward or off-set with respect thereto. It will further be observed that this clip or clamp is integral with the upwardly and rearwardly inclined buckle holding section to which the buckle may be attached by means of the oppositely disposed tongues and the buckle bar, as shown in Fig. 1.

Now, due to the thin metal from which the holder is made, it is inherently resilient and the jaws will have a certain amount of resiliency or spring clamping action.

In use, the clip or clamp portion of the holder is slipped on to the vamp of the shoe, as shown in Figs. 2 and 5, and the sharpened prongs, owing to their direction of projection, will not bite into the material of the vamp

but will allow the clamp to be slipped into position on the vamp. Should, however, there be a tendency of the holder to work loose, or the clamp to work up and off from the vamp, the direction of projection of the prongs will cause the latter to bite into the material of the vamp and hold the clamp in position, and at the same time the tendency of the nibs on the clamping section will be to force or wedge the material of the vamp tightly against the prongs, thus assisting in the tightening of the biting action of the prongs.

The result is that the greater the tendency of the holder to work off from the vamp the tighter will be the binding and biting action of the nibs and the prongs respectively, and their combined action will insure against the accidental displacement of the buckle support. Owing to the resilient nature of the material of the holder the jaws may be bent slightly in applying the holder and then pressed toward each other or tightened, as will be readily understood.

While I have herein shown and described one embodiment of my invention, I wish it to be understood that the same is not limited to all the precise details of construction herein set forth by way of illustration, as modification and variation may be made without departing from the spirit of the invention or exceeding the scope of the appended claim. For example, as the present invention is particularly adapted to the construction of the clamp or clip section of the support as contradistinguished from the upper or buckle supporting section thereof, the invention is not limited to use with such a buckle supporting section as is shown herein as the latter may be of any suitable construction, and the buckle may be secured to the holder in any desired manner either permanent or detachable.

What I claim is:

In a support of the class described, a vamp embracing clamping section comprising two jaws, an upper and a lower jaw, adapted respectively to fit over and under a vamp, the upper jaw having a vamp engaging nib, and the lower jaw having a vamp engaging prong, the nib and the prong being offset with respect to each other and so relatively located that the nib tends to cause the prong to penetrate the material of the vamp upon attempted movement of said support off the vamp.

Signed at New York city, in the county of New York and State of New York, this 9th day of March, A. D. 1928.

MATTHEW J. KEEVERS.
